UNITED STATES PATENT OFFICE

KENNETH GLEASON, OF HIBBING, MINNESOTA

CABLE-TERMINAL HOOK

Application filed September 27, 1929. Serial No. 395,641.

This invention relates to cable terminal hooks and has special reference to such a hook for use in mining operations where quick and positive attachment of a cable to a bailer, drag, or the like, is essential.

The principal object of the device is to provide as efficient and easily manipulated a hook as possible.

Another object is to provide such a hook in which wear upon the cable to which it is attached is reduced to a minimum.

Still other objects and advantages of the invention will appear in the following description.

15 Referring now to the accompanying drawing forming part of this application, and wherein like reference characters indicate like parts:

The illustration is that of an elevation of 20 one of the improved hooks as applied to a hoisting cable for bailing purposes.

1 in the drawing represents the cable, one end of which has formed therein the eye or bight 2 by means of the common cable 25 clamp 3. This bight is directly connected to the eye 4 formed in the goose-neck end of the hook and thus provides a loose pivotal connection therewith.

The hook is novel in that it is formed with 30 the goose-neck 5 as a natural wearing member for the objects engaged, such as the handle of a bailer, clevice, or the like, and the elongated straight body portion 6 intermediate of the goose-neck and the upper 35 open helical terminal 7. This latter I am aware is not novel in the art of cable terminals and forms but a cooperative part of my present novel combination hook.

A further novel feature of the device is 40 that the lower or goose-neck end of the assembly is wider, that is transverse the axes thereof, than at any other point, thus causing the brunt of abuse by way of frictional contact with the sides of a drill hole or the 45 like coming upon the larger or looped end of the hook, that is at least little if any coming upon the cable.

The convenience of being able to quickly 50 release or attach the open helical end of the hook to the main portion of the cable

is obvious as is also the protection afforded the cable at this point.

Having thus described my invention, what I claim and desire to secure by Letters Patent, is:

A hook of the class described, helically shaped at one end, and having a hook at the opposite end terminating in an eye, an elongated substantially straight body portion intermediate the hooked end and the helical portion, the axis of the eye being at an angle to the axis of the hook for the purpose described.

In testimony whereof I affix my signature.

KENNETH GLEASON.
